DAVID H. FANNING'S
DESIGN FOR CORSETS.

PATENTED SEP 27 1870

Witnesses

Thos. H. Dodge
Chas. H. Nichols

Inventor

David H. Fanning

United States Patent Office.

DAVID H. FANNING, OF WORCESTER, MASSACHUSETTS.

Design No. 4,366, dated September 27, 1870.

DESIGN FOR A CORSET.

The Schedule referred to in these Letters Patent and making part of the same.

To all whom it may concern:

Be it known that I, DAVID H. FANNING, of the city and county of Worcester, and State of Massachusetts, have invented and produced a new and original Design for Corsets, of which the following is a full and clear description, reference being had to the accompanying drawing, which represents a perspective front view of a corset made in accordance with my design.

The nature of my design is fully illustrated by the drawing, from which it will be seen that the upper and lower bindings, or supporting-pieces, A B, are united by separate upright pieces, C, the central parts

of which are joined to zone-shaped pieces, D D, which form the waist or girdle of the corset, while the spaces between the upright pieces C, above the girdle D, are covered with open-work cloth or netting, E, and the similar spaces below the zone-shaped girdle D are left open, thus producing a very tasty and neat design for corsets.

I claim as my invention—

The design for a corset, as shown and described.

DAVID H. FANNING.
